UNITED STATES PATENT OFFICE

FREDERICO ANTON KOWARICK, OF SAO PAOLO, BRAZIL

VALVE GEAR FOR STEAM ENGINES

Application filed January 9, 1929, Serial No. 331,263, and in Germany January 16, 1928.

The invention relates to a valve gear for high speed engines, working with superheated steam, particularly multiple expansion engines, the piston of which reciprocates at a speed of 6 to 12 metres in the second. Such a valve gear must answer the following requirements:

(1) Variable cut-off within wide limits.
(2) A constant or a decreasing lead or a

reduction of the load at the discretion of the designer.

(3) Absolute zero admission.

(4) Balance of cut-off as well as of working, and

(5) Avoiding of every reaction on the regulator.

These requirements are fulfilled by the valve gear according to the present invention to full extent. This invention is characterized by the fact that the eccentric is made of two sections, namely an inner section journaled rotatably on the valve gear shaft, and an annular section rotary on the circumference of the first named section.

The circumference of the outer section which is eccentric to the circumference of the inner section is surrounded by an eccentric strap, the two sections being adapted to rotate simultaneously relatively to the valve gear shaft but in different directions to one another, the object being to secure any desired admission ranging between absolute zero admission and eventually highest admission, even during the operation of the machine, and at the same time increasing or decreasing the lead corresponding to the degree of cut-off proportionally, or even to keep it constant.

To enable an adjustment of the two eccentric sections a rotatable and slidably adjusting member is arranged on the valve gear shaft by the aid of a spiral guide. The adjusting member acts on the annular section of the eccentric by the aid of curved slot guides and on the inner section of the eccentric by the aid of another spiral guide of different inclination. The eccentric strap by the aid of cam guides operates the inlet members of the cylinder. These cam guides

as well as the valve gear eccentric run in a bath of oil to guarantee an easy run.

Fig. 1 of the drawings is a sectional elevation of a cylinder.

Fig. 2 is a cross section of a sectional valve gear eccentric taken on the line I—I of Fig. 4.

Fig. 3 is an end view of the eccentric shown in Fig. 2.

Fig. 4 is an end view, and

Fig. 5 a side view of the inner eccentric section, and

Fig. 6 illustrates a spiral guide of the valve gear shaft carrying the adjusting member.

Figs. 7, 8, 9 and 10 are diagrams serving for determining the shape of the spiral guides and the cam slots.

The steam inlet and outlet of the cylinder *a* having a piston *t* of the machine shown in Fig. 1 is effected by the aid of a slide valve *c*. The slide valve rod *n* is operated by cams *e* which are operated in pairs by rods *f* with one another. By the aid of the eccentric straps *h* and links *i* the eccentrics *g* mounted on the valve gear shafts *k* operate the rods *f*. The eccentrics *g* as well as the cams *e* run preferably in oil baths not shown.

In the construction shown in Figs. 2 to 6 the eccentric comprises an inner section *g'* having a circular circumference on which the section *g''* is adapted to rotate and which itself is rotatably journaled on the valve gear shaft *k*. The outer section *g''* is surrounded by an eccentric strap *h*, the circumference of the outer section *g''* being eccentric to the circumference of the inner section *g'*. The latter *g'* is integral with the socket *m*, which is provided with a helical slot *n*. The annular section *g''* is provided with two lateral projections, on which pins *o* are mounted.

The valve gear shaft *k* has a thickened part or collar *p*, into the cylindrical surface of which a helical slot *q* is cut. A disk *r* is provided with two opposite bosses *s* and *s'*, which embrace the socket *m* and the collar *p* respectively. The bore of the boss *s* is provided with a helically shaped projection, which enters the helical slot *n* on the socket *m*, and the bore of the boss *s'* is provided with a helically shaped projection, which

enters the helical slot q of the collar p . On the outer circumference of the boss s' between two ball bearings t a ring u' is held in position by two nuts w and provided with two arms u^2 , which are connected with a fork u by screw bolts u^3 . The fork u is firmly pivoted and the outer end x may be connected with any known rodding not shown for regulating the cut-off.

10 When the rodding is operated the fork u transmits a longitudinal movement to the disk r on the collar p of the shaft k . By the aid of the helical thread q the disk r and simultaneously therewith the outer eccentric section g^2 is rotated by the intermediary of the pins o and the slots r' of the disk r . The amount of rotation depends on the previously calculated inclination of the helical thread q and the longitudinal movement on the collar p .

15 At the same time with these movements the helical thread n causes a rotation of the socket m together with the inner eccentric section g' in opposite direction, corresponding to the inclination of the helical thread n . Thus the rotation of g' and g^2 enables different circles of stroke, which then effect by the cam e any desired admission at will and according to the construction. It is the 20 task of the designer by causing a rotation of the inner section g' to the correct angle either to secure a constant or a variable lead, that is to say a proportionally reducing lead when the load of the machine is reduced, 25 as well as when it is a question of heavy stationary machines to secure a balance of working, which eventually is to be found out.

30 In the Figs. 7 to 10 the manner of deciding the dimensions is explained. According to Fig. 7 first of all a minimum circle of stroke is to be chosen or calculated. This circle will be described as circle 1. Thereupon the larger circle of stroke 2 is drawn. These proportions g' and g^2 bounded by 35 these circles 1 and 2 represent the two eccentric sections. 0 is a center of the valve gear shaft and $0'$ a center of g^2 . It is the condition that the center $0'$ is situated on the minimum circle 1 of the stroke. Now a line 3 is drawn 40 at an angle of 30° to the horizontal tangent of the circle 1 at the point $0'$. The line 3 intersects the circle 2 at the point 4. By the aid of a pair of compasses the distance $0'-4$ is taken and by this a circular arc is 45 described on the vertical. The center 0^2 of this circle will then be the found center for g' . Not until now can the size of the eccentric be determined.

50 In the Fig. 8 g' is taken to be fixed on the shaft, while g^2 is rotated about 60° . 1 is the outer diameter of g' on the circumference of which g^2 must move. When now g^2 is rotated from the point 2 to the point 3 the center $0'$ of g^2 will move on the half circle 55 4 from $0'$ to 5^a . When g^2 is moved further

up to 60° the center of g^2 will be at the point 6, and the distance 0-6 is the radius of the largest circle of stroke. This circle of stroke will of course be larger when the rotation of g^2 is continued.

60 If the hatched segment, shown in Fig. 8, is intended for a certain cut-off and g^2 is rotated alone for itself from the points $0'-6$ the different admissions will be understood. Thus the angle of lead, Fig. 8, with respect to 0% admission would vary up to the unknown admission from 0% up to 30° , since the crank shaft is firmly connected with the valve gear shaft.

65 To balance the difference of 30° in such manner that a correct opening is secured at any desired cut-off, g' will be rotated in the opposite direction. This will be understood from Fig. 9, which for better illustration is drawn to a scale twice as large as that of 70 Figs. 7 and 8. We proceed at first exactly in the same manner as in Fig. 8, all circles and lines are drawn, and also a segment for any desired cut-off. The line A-B is thus the desired opening line for any cut-off, and 75 now one has to try to practically approach the center of g^2 this line. This is done in the following manner: If the largest cut-off is desired, g^2 will be rotated for 60° , so that its center $0'$ will be at 18. Now g' must be so 80 shifted, that the point 18 wanders towards A. The length 18-A will be taken into the compasses and cut-off from the point 7 on the same circle of stroke, thus finding the point 8. When now a straight line is drawn from 0 through 8 the angle of rotation for g' is found 85 at 14.4° . When then the arc 10 is drawn for the sake of checking that what is found, that is to say the path of the center of g' , the compasses are set in at 9 and the circle 14 is 90 drawn for g' , and also when set in in A the circle 15 for g^2 the correctness of the rotation 95 will be recognized. The line A-9-17 shows the new opening of g^2 . Thus the 100 admission is correctly adjusted.

105 Now the eccentric sections g^2 and g' are proportionally moved by the helical guides, that is to say 15° for g^2 and 3.6° for g' . If now g^2 is standing at an angle of 45° and g' at an angle of 10.8° the center g^2 will be at 11. The opening of the valve however cannot take place until at the point 13. Therefore the valve gear shaft and the crank shaft must 110 rotate forwardly for the angle β and the admission will take place later for this angle β . This is of advantage since for small fillings a slighter admission is desirable. However, even by other rotation of g' a constant lead can be secured. In this case the center 115 wanders on a straight line.

120 If the crank 1 is in the position shown in Fig. 9 the eccentric in zero position of the crank must have a lead for an angle α . By rotation the openings must correspond to the 125

fillings or admissions since the point g^2 wanders towards A.

The Fig. 10 serves for determining the helical slots r' on the disk r for the entraining pins o of the eccentric section g^2 , thus for rotating the latter. Since now the center of g^2 has moved from 0' up to A, the disk r is rotated about its center coinciding with the center of the valve gear shaft. The entraining pins o of the annular section g^2 according to Fig. 10 describe the curved paths 3—5—9—11—13 and 4—6—10—12—14 respectively, while on the disk r they describe the curved paths 3^a — 3^b — c^e — 3^d —13 and 15 4^a — 4^b — 4^c — 4^d —14 respectively. The corresponding helical slots must be machined very carefully. The points 3 and 4 are the distances of the entraining pins o with reference to the center of g^2 .

20 The drawing of the curved paths is effected as follows: At first all the lines and circles are drawn as is done in Fig. 9. We have seen that the line A—9—17 is the new eccentric position corresponding to an angle of 60° for g^2 and of 14.4° for g' . This line will now be drawn up in Fig. 10, thereupon a vertical line A' through the point A and on this vertical line the distances of the entraining pins o are cut-off, so that the points 13 and 14 25 are found. Now we go back for 15° for g^2 and 3.6° for g' respectively, and draw the line 1^a through 1—2 and the vertical 1^b and designate the points 5 and 6. In similar manner the line 7^a , the vertical 7^b , the points 30 9 and 10 are drawn until all points are found. Thereby the curved path of the pins is given.

The same is to be done with regard to the curves on the disk r . The arcs 25 and 26 are described with the radius 0—3 and 0—4 respectively, and the arcs 25 and 26 divided into four portions of each 15° , which may signify the partial rotation of the disk r . When now the disk r is rotated from 15 to 19 also the point 20 wanders to 24, while the entraining pins o stand at 13 and 14. Now one shank of the compasses is set in at 0 and the lines 0—5, 0—9 and 0—6, 0—10 and so on are taken, and then the arcs are drawn. Thereupon the pieces 15—3, 16—5, 17—9 and 20—4, 21—6, 45 22—4 respectively are taken one after the other and transmitted from 19 and 24 respectively on the corresponding arcs. Thus also the curved paths of the disk r are decided.

The calculation of the helical guides g and n is carried out in simple manner. Assumed the adjusting member s' will be shifted about 30 mm. parallel to the shaft and at the same time rotated about 60° the length for one turn will be found from the equation

$$\frac{360}{60} \times 30 = 180 \text{ mm.}$$

Since g^2 rotates about 60° g' must simultaneously rotate 14.4° in opposite direction during the rotation of g^2 , thus it will be moved

for $60 + 14.4 = 74.4^\circ$. The length of the inclination of one turn is thus found to be

$$\frac{360}{74.4} \times 30 = 145.16 \text{ mm.}$$

If a less inclination is desired the curve of groove must be prolonged correspondingly.

I claim:

1. An eccentric valve gear for steam engines comprising a valve gear shaft, a sectional eccentric, one section of said eccentric being mounted upon said shaft, an eccentric strap, a second section of said eccentric having an inner diameter corresponding to the outer diameter of said first mentioned section and its outer diameter corresponding with the inner diameter of said strap, said two sections being eccentric to one another and rotatably mounted relatively to said valve gear shaft but in opposite direction to one another in order to secure any desired cut-off between the absolute zero-cut-off and a given maximum cut-off even while the engine is running and the lead may be adjusted also corresponding to the cut-off in question proportionally increasing or decreasing or may be held constant, an adjusting member mounted rotatively and longitudinally shiftable on the valve gear shaft with a helical connection, said adjustable member having a curved slot guide arranged to act on the said second section and said adjustable member having a further helical connection of different inclination arranged to act on the said first section, a fork for operating said adjusting member, a thickened part or collar on the valve gear shaft, a disk, curved slots in said disk, entraining pins on the second section of the eccentric projecting into said curved slots in said disk, a socket on the first mentioned section of the eccentric forming a boss surrounding the inner part of the valve gear shaft, a hollow boss on the disk fitted on the said socket and connected thereto by a helical connection.

2. An eccentric valve gear for steam engines comprising a valve gear shaft, a sectional eccentric, one section of said eccentric being mounted upon said shaft, an eccentric strap, a second section of said eccentric having an inner diameter corresponding to the outer diameter of said first mentioned section and its outer diameter corresponding with the inner diameter of said strap, said two sections being eccentric to one another and rotatably mounted relatively to said valve gear shaft but in opposite directions to one another in order to secure any desired cut-off between the absolute zero-cut-off and a given maximum cut-off even while the engine is running and the lead may be adjusted also corresponding to the cut-off in question proportionally increasing or decreasing or may be held constant, an adjusting member mounted rotatively and longitudinally shiftable on

said valve gear shaft with a helical connection therewith, said adjustable member having a curved slot guide arranged to act on the said second section and said adjustable member 5 having a further helical connection of different inclination arranged to act on the said first section.

In testimony whereof I have signed my name to this specification.
